US00D977495S

(12) **United States Design Patent** (10) Patent No.: **US D977,495 S**
 Diptiman et al. (45) Date of Patent: ** Feb. 7, 2023

(54) **DISPLAY SCREEN OR PORTION THEREOF WITH GRAPHICAL USER INTERFACE**

(71) Applicant: **Toyota Motor North America, Inc.**,
 Plano, TX (US)

(72) Inventors: **Tuhin Diptiman**, Plano, TX (US);
Daniel Hall, Dallas, TX (US); **Louie Solomon**, Richardson, TX (US); **Ben Cline**, Salt Lake City, UT (US); **John Weston Pierce**, Salt Lake City, UT (US)

(73) Assignee: **Toyota Motor North America, Inc.**,
 Plano, TX (US)

(**) Term: **15 Years**

(21) Appl. No.: **29/760,877**

(22) Filed: **Dec. 4, 2020**

(51) LOC (14) Cl. **14-04**

(52) U.S. Cl.

USPC **D14/485**; D14/489

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost dashed lines in the FIGURE show a display screen or portion thereof and form no part of the claimed design. The other dashed lines show portions of the graphical user interface that form no part of the claimed design.

1 Claim, 1 Drawing Sheet
